VENDING MACHINE

Albert E. Gebert and Myron H. Richardson, Wilmette, and Floyd C. Black, Chicago, Ill., assignors to Advance Machine Co., Chicago, Ill., a corporation of Illinois

Application October 31, 1938, Serial No. 237,856

15 Claims. (Cl. 312—94)

This invention relates to improvements in vending machines of the type in which the supports for the articles to be vended are arranged in a column consisting preferably of downwardly inclined supports, one above the other and properly spaced to receive the articles therebetween, each support holding the separate articles or commodity.

Holding means are provided which co-operate with the article supports, the respective holding means when shifted, operating to release the article so that one may be delivered from the support to the operator of the machine, and another article will replace the one vended, as long as the reserve supply lasts.

It is one of the objects of the present invention to provide improved means for holding a plurality of articles upon the same support, one in advance of the other, and improved means for successively releasing the articles to be vended upon the proper operation of the machine, thereby insuring that a sufficient supply will be held in reserve to be automatically positioned to be delivered after the delivery of the foremost article and until the reserve supply has been exhausted.

A further object is to provide improved means for keeping the articles upon the respective supports separated from each other, and also improved means for locking the separating means against operation.

A further object is to provide an improved means for actuating the locking mechanism to actuate the separating means to release the article.

To the attainment of these ends and the accomplishment of other new and useful objects as will appear, the invention consists in the features of novelty in substantially the construction, combination and arrangement of the several parts, hereinafter more fully described and claimed and shown in the accompanying drawings illustrating this invention, and in which—

Figure 1 is a front elevation of a portion of a machine, with parts broken away, constructed in accordance with the principles of this invention.

Figure 2 is a rear elevation of Figure 1, with the back of the machine removed.

Figure 3 is a vertical sectional view, on an enlarged scale, and with parts omitted and parts broken away, as taken on line 3—3, Figure 1.

Figure 4 is a detail sectional view, with parts omitted and on an enlarged scale, as taken on line 4—4, Figure 2.

Figure 5 is a detail sectional view taken on line 5—5, Figure 4.

Figure 6 is a detail sectional view taken on line 6—6, Figure 4.

Figure 7 is a sectional plan view, with parts 5 broken away and on an enlarged scale, as taken on line 7—7, Figure 4.

Figure 8 is a detail sectional view, on an enlarged scale, taken on line 8—8, Figure 7.

Figure 9 is a view partly in elevation and partly 16 in section as taken on line 9—9, Figure 8.

Figure 10 is a detail sectional view, on an enlarged scale, taken on line 10—10, Figure 7, showing the parts in one position.

Figure 11 is a right hand end elevation of 15 Figure 10.

Figure 12 is a view similar to Figure 8, showing the parts in a different position.

Figure 13 is a detail perspective view of the locking means for a supplemental article retainer. 20

Referring more particularly to the drawings, the number 15 designates generally an enclosing casing which may be of any desired size and configuration and constructed of any suitable material, having arranged in the bottom thereof a 25 chute 16 upon which the articles are deposited and from which the articles are delivered through a delivery opening 17, to the operator.

The front of the casing may be provided with a transparent portion 18 through which the 30 articles may be viewed, and the casing may be provided with a removable back or closure 19.

Arranged within the casing are a plurality of superposed supports 20 which incline downwardly towards the front of the casing, but terminate 35 a considerable distance from the front wall of the casing to form a passage 21, into which the articles are delivered as they fall from the respective supports 20, and through which passage the articles will fall until they strike a deflector 22 40 supported at the bottom of the passage 21 and extending below the series of supports 20, to direct the article to the chute 16, thereby rendering it possible for the operator to at all times view the article while it is resting upon the support 45 20 and while falling through the passage 21.

Any number of these supports 20 may be provided and are arranged any desired or suitable distance above each other to accommodate the various articles to be dispensed.

Co-operating with each of the supports is an article holder or retaining device 23, preferably formed as a bale of a substantially U-shaped configuration, and the extremities of the sides of the bale are pivotally mounted as at 24 in 55

uprights 25 (see particularly Figure 7) which are spaced from uprights 26 arranged at the respective ends of the supports, so that the ends of the bales or arms of the article holding or retaining guards will be disposed in the space formed between the uprights 25 and 26.

These article holders or retaining devices are mounted for free pivotal movement and connected to the extremity of one end of each is a depending arm 27 (see particularly Figure 11), for a purpose to be hereinafter set forth.

These holders or retaining devices are adapted to be swung about their pivots so as to release the article upon the support with which the holding device co-operates, in any desired or suitable manner, but a simple and efficient means embodies a slide 28 of any suitable configuration and provided with a body portion having a slot 29 therein, through which slot fastening pins or members 30 pass to engage a fixed support so as to hold these slides in proper position.

One of the slides is provided for each of the article holding or retaining devices 23 and carries a lip or projection 31 which engages the depending arm 27 when the slide is moved in one direction to swing the article holder or retaining means 23 about its pivot 24 to release the article from the co-operating support 20.

A spring 32 (see particularly Figure 10) tends normally to move the slide 28 in a direction to lower the article holder or retaining means 23. The lip or shoulder 31 is formed preferably in a flange on the member 28, and such flange is cut away to provide a space into which the depending arm 27 projects (as shown in Figure 10).

Carried also by the slide 28 is an arm or projection 33 which is adapted to be engaged by a pawl 34 pivotally mounted as at 35 (see particularly Figures 2 and 7) upon a member 36, a stop 37 being provided to limit the movement of the pawl 34 in one direction, and a spring 38 tends normally to hold a portion of the pawl in engagement with the stop 37.

The member 36 is mounted for sliding movement upon a bar or rod 39, which latter is preferably angular in cross section and is pivotally mounted by its ends in brackets 40 so as to rotate on a vertical axis, thereby permitting the member 36 to rotate on the same axis to move the pawl 34 into engagement with the arm or projection 33 on the slide 28 when the member 36 is moved in one direction, to raise the article holding member or retainer 23, the slide 28 moving against the stress of the spring 32. When, however, the member 36 is rotated in the opposite direction, the slide 28 will be held against movement by means of the spring 32 holding the end of the slot 29 in engagement with one of the fastening means 30. The pawl 34 will then swing about the pivot 35 against the stress of the spring 38 so as to pass by the arm or projection 33 and into a position that upon the next rotation of the member 36, the slide 28 will again be actuated against the stress of the spring 32 to raise the article holding or retaining member 23.

Any suitable means may be provided for rotating the member 36, but a simple and efficient means embodies a bell crank lever 41 pivotally mounted as at 42. Connected to the lever as at 43 is a link 44 which is also connected as at 45 with the bar or rod 39.

The lever 41 is adapted to be swung about its pivot by means of an operating knob or handle 46, and which handle constitutes a portion of a

coin controlled mechanism 47, having a slot 48 for the reception of the coin.

This coin controlled mechanism may be of any desired or suitable construction, suffice it to say that it is provided with a member 49 that is adapted to be actuated by the coin controlled mechanism, and this member 49 is in turn connected by means of a link 50 to the other end of the bell crank lever 41, as at 51.

With this construction and when a coin is deposited in the coin receiving opening 48, the coin controlled mechanism will be rendered active, and this will result in the actuation of the member 49 which, through the medium of the link 50 will rock the bell crank lever 41, and through the medium of the link 44 will turn the member 39 about its pivot to rotate the member 36, causing the pawl 34 to assume a position that in one direction of its movement it will engage the arm 33 on the slide 28 to move the latter against the stress of the spring 32, causing the shoulder or ear 31 to engage the depending arm 27 of the article holding or retaining member 23 to rock it about its pivot and thereby release the article.

When the handle 46 is moved in the opposite direction then the member 36 will be returned and the pawl 34 will yield to pass by the arm 33 on the slide 28, and the spring 32 will return the slide to its normal position, thereby allowing the article holder or retaining device 23 to assume its normal position, so that it will retain or hold an article upon the respective support 20.

The member 36 is adapted to be moved lengthwise of the rod or bar 39 in any suitable manner, such as by means of a sprocket chain 52 53 which passes over a sprocket wheel 53 and also over another sprocket wheel 54 arranged respectively in proximity to the ends of the bar 39.

An operating handle 55 arranged on the outside of the machine and preferably in proximity to the handle 46, is connected to a shaft 56 to which the sprocket wheel 54 is attached.

Carried by the member 36 is a pointer or indicator 62 which is positioned so that a portion thereof may be visible through the transparent member 18 in the front of the machine (see particularly Figure 1) and this indicator co-operates with graduations 63, one of which latter is arranged adjacent each of the supports 20.

In order to insure a proper positioning of the indicator 62 so as to properly position the dog 34 with respect to the mechanism which it is to release and operate, means are provided for locking the parts in their adjusted position when they have acquired such position.

To that end there may be provided on the shaft 56 (see particularly Figures 4 and 6) a disc 57 having notches 58 in its periphery. A member 57^a is pivotally mounted as at 57^b and is provided with a laterally projecting portion 60 which may, if desired, be in the form of a roller adapted to be held in contact with the periphery of the disc 57 by means of a suitable spring 61, so that when one of the notches 58 is in proximity to the projection 60, the spring 61 will cause the latter to enter one of the notches 58, it being understood that the notches 58 are arranged in proper position with relation to the positioning of the indicator 62.

In use, this pointer 62 is positioned by the handle 55 so that it will be in line with the particular graduation 63 that is adjacent the support 20 upon which the desired commodity rests.

By positioning the pointer 62, the member 36 will be positioned so that when the machine is

operated, the particular article holder or retaining device 23 will be raised in a manner already described.

A supplemental article holder or retainer 64 is provided for each of the supports 20 (see particularly Figure 3), and this retaining device is preferably in the form of a gate or member pivotally mounted by one edge as at 65 and positioned in an opening 66 in the support. When the retaining device 64 is in the position shown in Figure 3, it will hold an article in the rear thereof so that it will not be delivered and will maintain it separated from the article in advance thereof.

When, however, the forward article has been dispensed by raising the article holder or retainer 23 at a predetermined time in its return movement to the position shown in Figure 3, the locking mechanism for holding the supplemental retainer 64 will be released and the retaining device 64 will be free to move under the weight of the article therebehind into a position that the article formerly held thereby will move upon the support 20 into a position to be held by the holder or retaining device 23 to replace the article previously delivered, to be delivered when the holding or retaining device 23 is again elevated.

Carried also by the shaft 56 is another disc 67 (see particularly Figure 5) which is provided with recesses 68 opening through its periphery, and which recesses are preferably in alignment with the recesses 58.

A slide 69 mounted to move upon a suitable guide 70 is provided with a slot 71 through which a fastening screw 72 passes.

One end of this slide 69, which slide is preferably in the form of a bar, is adapted to enter the recesses 68. The slide is given its movement by means of a bell crank lever 73 to which one end of the slide 69 is connected as at 74. To the other end of the bell crank lever 73 a link 75 is pivotally connected as at 76, and the other end of the link 75 is pivotally connected as at 77 to a disc 78 of the coin controlled mechanism, and to which disc 78 is also connected the member 49.

The supplemental article retainers 64 (see particularly Figures 8 and 9) are held in a locked position, that is so that the article resting upon the support 20 therebehind will be maintained separated from the article resting on the forward part of the support 20 and against movement toward the forward end of the support by means of locking mechanism which consists of a member 79 which is pivotally supported as at 80 upon a fixed support. This member is preferably shaped to form arms 81-82, and carried by the arm 81 is a laterally projecting pin or extension 83. A spring 84 encompasses the pivot 80 and one end of the spring engages the projection 83 and tends normally to hold the arm 81 against a stop 85.

A counterbalancing weight 86 may also be carried by the member 79, which will assist the spring 84 in its action, and a stop 87 is provided for limiting the movement of the member 79 about its pivot, the stop 87 operating in opposition to the stop 85.

Carried also by the member 79 and by the arm 82 thereof, is another member or dog 88 which is pivotally supported by the arm as at 89. The dog 88 is provided with an extended extremity or surface 90 adapted to be engaged by a pin or projection 91 carried by one of the arms of the article holder or retainer 23.

The member 88 is provided with a bifurcation

92 forming the arms 93-94, and a pin or lug 95 is carried by a fixed part of the machine and projects into the bifurcation 92.

The member 88 is adapted to swing freely about the pivot 89, as is also the member 79. The member 79 is limited in its swinging movement about its pivot 80 by means of the stops 85-87, while the arms 93-94 co-operating with the pin or lug 95 operate to limit the swinging movement of the member 88 about its pivot 89.

The supplemental article retainer or holder 64 is provided with a depending arm 96 having a laterally projecting extremity 97, and this arm 96 is so positioned that when the supplemental retainer 64 is in a position with respect to the support 20 to maintain an article or commodity therebehind, the member 79 will also be in such a position that the pin or projection 83 carried by the member 81 will be in a position that the extremity 97 of the arm 96 will rest thereupon and thereby lock the supplemental retainer or holder 64 in an operative position as shown by the second unit from the bottom of Figure 8.

When the supplemental retaining member 64 is in a locked position, the article retaining or holding member 23 will be in an operative position, that is in a position to hold or maintain the article upon the support 20, or in the position shown by the second unit from the bottom of Figure 8.

At this time, that is when the retaining member 23 is in an operative position, the pin or projection 91 will be disposed so that the face 98 of the member 88 will rest thereagainst and the arms 93-94 of the member 88 will be out of engagement with the pin or projection 95.

When the parts are in this position, or in the position shown by the second unit from the bottom of Figure 8, an article will be held by the retaining means 23 and another article by the supplemental retainer 64.

When this retainer 23 is raised in the manner already described, by operating the slide 28 (see Figure 10) to swing the article holder or retaining member 23 about its pivot by means of the shoulder or ear 31 (see Figure 11) engaging the depending arm 27 of the retaining member 23, the pin 91 will move along the face 98 of the member 88 until it has passed out of engagement with the member 88, and at that moment the member 88 will swing by gravity about the pivot 89 until the arm 94 engages the pin or stop 95. During this entire movement the extremity 97 of the arm 96 of the supplemental retaining device 64 will remain in a locked position by reason of the extremity 97 resting upon the pin or projection 83 of the member 79.

The upward movement of the article holder or retaining member 23 will be limited by means of a stop device 99.

The parts will remain in this position until the retaining member 23 is lowered. During the lowering movement of the retaining member 23, the pin or projection 91 will engage the end or surface 90 of the member 88, as shown in the lower unit of Figure 8, and a continued movement of the retaining member 23 downwardly will bodily force the member 88 downwardly, causing the member 79 to swing about its pivot 80 so that the pin or projection 83 will be moved out of engagement with the extremity 97 of the arm 96 of the supplemental retainer 64, thereby releasing or unlocking the supplemental retaining member 64, so that the weight or pressure of the article behind the retaining member 64 will cause

the latter to swing about its pivot from the position shown in the second unit from the bottom of Figure 8 to the position shown in the bottom unit of Figure 8, to release the article and allow the same to slide forwardly upon the support 20 to be retained or held by the retaining member 23.

Just at the time that the pin 83 is moved away from the extremity 97 of the arm 96, the retaining member 23 will have assumed its operative position 10 with respect to the support 20.

As the member 88 is bodily lowered causing the member 82 to swing about its pivot 80, the member 88 will also swing about its pivot by reason of the arm 94 contacting with the pin or projection 15 95.

In order to reset the locking mechanisms embodying the member 88, there is provided a bar or member 100, which is provided with arms 101 so shaped that they will pass under the respective 20 arms 96 of the supplemental retainer 64, when the bar or member 100 is bodily moved lengthwise, to rock the supplemental retainers 64 about their pivots into an operative position and at the same 25 time position the arms 96 so that the extremities 97, when the bar or member 100 is returned, engage and rest upon the projections 83 of the members 89.

The bar or member 100 is supported by bell 30 crank levers 102, any number of which may be provided, and each one of these bell crank levers is pivotally mounted intermediate its ends as at 103 upon a stationary part of the machine, and the bell crank levers are connected by one end as at 104 to the bar or member 100. The connecting pins or members 104 pass through curved 35 slots 105 in a stationary member 106, and on which member 106 are stops 107 for limiting the movement of the arms 96 and consequently the supplemental retaining member 64 in one direction 40 under the influence of the arms 96 when the machine is being reset for operation.

The curved slots 105 permit of the proper movement of the bar or member 100.

The other end of the bell crank levers 102 are 45 pivotally connected as at 108 to an actuating bar or member 109, one end of which latter is formed into a finger engaging portion 110. A spring 111 is anchored as at 112 to a fixed support and is connected as at 113 to the bar or member 109.

50 Thus, when the bar or member 109 is moved downwardly, the bell crank levers 102 will swing about their pivots 103, carrying with them the bar or member 100, the curved slots 105 permitting of the proper movement of the bar or member 100.

This movement of the bar 100 will move the arms or projections 101 thereon into engagement with the arms 96 to swing the supplemental retainers or article holders 64 into an operative position and to hold them in such position until the pins 83 are moved under the extremities 97 and thereby lock the supplemental retainers or holders 64 in operative positions.

The weight 86 carried by the member 79 serves 65 to counterbalance the member 88, and this weight together with the spring 84 operate upon the member 79 to swing the same about its pivot and to raise the member 88 so that they will be in position that the pin 91 will engage and shift 70 both the member 79 and 88 to release the supplemental retainer 64 as the retainer 23 moves into operative position.

While the preferred form of the invention has 75 been herein shown and described, it is to be understood that various changes may be made in

the details of construction and in the combination and arrangement of the several parts, within the scope of the claims, without departing from the spirit of this invention.

What is claimed as new is:

1. In a vending machine an article support, a plurality of separate article retaining means co-operating with the support, means for actuating one of the retaining means to release the article held thereby, locking means for the other retaining means, said locking means embodying a pivotally mounted locking element, a second element mounted upon the said locking element for bodily movement therewith and for movement with respect thereto, means connected with the actuated retaining means for engaging the second said element to swing the locking element about its pivot to render the last said locking element inactive, and means for causing the said second element to be moved with respect to the said locking element during its bodily movement with the latter whereby to position the said second element to lock the said one of the retainers. 10 15 20

2. In a vending machine an article support, article retaining means co-operating with the support, means for actuating said retaining means to release the article held thereby, a supplemental retaining means, locking means for the said supplemental retaining means, said locking means embodying a pivotally mounted locking element, an element mounted upon the said locking element for movement therewith and also with respect thereto, means carried with the actuated retaining means for limiting the movement of the second said element with respect to the locking element when the latter is in an active position with respect to the supplemental retaining means, said second element moving with respect to the said locking element upon 30 35 40 movement of the actuated retaining element in one direction, to a position to be engaged by the said means which is carried by the actuated releasing element during the movement of the latter in another direction, to swing the locking 45 element about its pivot to render the latter inactive to release the said supplemental retaining means.

3. In a vending machine a support constituting the sole support for the articles, a plurality of 50 separate retaining means other than said support for retaining the articles upon the support, means for actuating one of the retaining means to release the article held thereby, locking means for the other retaining means, said locking means embodying a pivotally mounted locking element, an element mounted upon said locking element for movement therewith and also with respect thereto, and means carried with the actuated retaining means adapted to engage the second 55 60 65 said element upon the movement of the actuated retaining means in one direction for shifting said locking element to render the other of said retaining means inactive.

4. In a vending machine a support constituting 65 the sole support for the article, article retaining means separate from the support and movable into and out of active position with respect to the support, means for thus moving said retaining means, a supplemental retaining means also 70 co-operating with the support to hold another article, locking means for the supplemental retaining means, said locking means embodying a pivotally supported element, a second element, said elements pivotally connected together, 75

- means pivotally supporting one of the elements, one of said elements constituting a locking element, actuating means carried with the first said retaining means for engaging the other of said elements to shift the locking element to render the latter inactive, and means whereby when the first recited retaining means is moved in one direction, the said other element will be automatically positioned to be shifted to actuate the locking element upon the movement of the first said retaining means in the opposite direction.
5. In a vending machine an article support, a retainer for retaining the article upon the support and being movable into and out of active position with respect to the support, a supplemental article retainer also co-operating with said support and movable into and out of active position with respect thereto, a locking element 10 for the supplemental retainer, means mounting said element for movement into and out of active positions, and means responsive to the actuation of the first said retainer for rendering said locking element active and inactive, the last 15 said means embodying a second element pivotally mounted upon and also movable with the said locking element, a projection on the first said retainer adapted to engage and move the second said element and thereby render the first said 20 element inactive.
6. In a vending machine, an article support, a pivotally mounted retainer co-operating with the support for holding the article thereupon, a projection carried by said retainer, a pivotally 25 mounted locking element, means tending normally to move said element into an active position to be engaged by said projection, a second element carried by the said locking element for movement therewith and with respect thereto, a second 30 article retainer movable into and out of active positions with respect to the support, means connected with the last said retainer, adapted to engage and move said second element to shift the locking element to render the latter 35 inactive when the second said retainer is moved in one direction, and means tending normally to move the second said element into a position to be engaged by the last said means, the third recited means operating automatically upon the 40 movement of the second said retainer into a position to release the article on the support held thereby.
7. In a vending machine an article support, a pivotally mounted retainer co-operating with the support to hold the article in position thereupon, a shoulder on the retainer, a pivotally 45 mounted locking element, means tending normally to move said element into a position to be engaged by said shoulder to lock said retainer, a second element carried by the locking element for movement therewith and with respect thereto, a second retainer for the articles movable into and out of active positions with respect to said support, a formation on said second retainer to engage said second element to render the locking element inactive when the said second retainer is moved in one direction, the 50 said formation serving when the last said retainer is in an active position with respect to the support, as a stop to limit the movement of the second said element in one direction about its pivot.
8. In a vending machine an article support, a plurality of pivotally mounted retainers co-operating with the support to hold the articles 55
- thereupon, locking means for one of the retainers, said locking means embodying a pivotally mounted locking element, a second element mounted upon the locking element for movement therewith and with respect thereto, means tending normally to render the locking element active, and means responsive to the operation of the other of the retainers, adapted to engage said second element to bodily shift it and with it the said locking element to render the latter 60 inactive with respect to said retainer.
9. In a vending machine an article support, a pivotally mounted retainer co-operating with the support to hold the article thereupon, locking means for the retainer, said locking means 65 embodying a pivotally mounted locking element, a second element mounted upon the locking element for movement therewith and with respect thereto, means tending normally to render the locking element active, and means adapted to 70 engage said second element to bodily shift it and with it the said locking element to render the latter inactive with respect to said retainer, the last said means embodying a second and pivotally mounted article retainer and an arm or projection connected therewith for engagement with said second element.
10. In a vending machine an article support, a plurality of separate and pivotally mounted retainers co-operating with the support to hold the articles thereupon, locking means for one of said retainers, said locking means embodying a pivotally mounted locking element, an arm on one of said retainers, means tending normally to 75 position the locking element to be engaged by said arm, a second element supported by the locking element for movement therewith and with respect thereto, an arm connected with another of the retainers, the last said arm adapted to engage and move said second element to shift the locking element when the last said retainer is moved in one direction, the last said arm also serving to control the movement of the second said element about its pivot, and a stop for limiting the last said movement of the last said element about its point of pivotal connection with the said locking element.
11. In a vending machine an article support, a plurality of separate and pivotally mounted retainers co-operating with the support to hold the articles thereupon, locking means for one of said retainers, said locking means embodying a pivotally mounted locking element, an arm on one of said retainers, means tending normally to position the locking element to be engaged by said arm, a second element supported by the locking element for movement therewith and with respect thereto, an arm connected with another of the retainers, the last said arm adapted to engage and move said second element to shift the locking element when the last said retainer is moved in one direction, the last said arm also serving to control the movement of the second said element about its pivot, a stop for limiting the last said movement of the last said element about its point of pivotal connection with the said locking element, and means for positioning the first said arm to engage the said locking element.
12. In a vending machine an article support, a plurality of separate and pivotally mounted retainers co-operating with the support to hold the articles thereupon, locking means for one of said retainers, said locking means embodying a pivotally mounted locking element, an arm on 80

one of said retainers, means tending normally to position the locking element to be engaged by said arm, a second element supported by the locking element for movement therewith and 5 with respect thereto, an arm connected with another of the retainers, the last said arm adapted to engage and move said second element to shift the locking element when the last said retainer is moved in one direction, the last said arm also 10 serving to control the movement of the second said element about its pivot, a stop for limiting the last said movement of the last said element about its point of pivotal connection with the said locking element, and counterbalancing 15 means for the said locking element.

13. In a vending machine an article support, a pivotally mounted retainer co-operating with the support to hold the article thereupon, a shoulder on the retainer, a pivotally mounted 20 locking element, means tending normally to position said element to be engaged by said shoulder to lock said retainer, a second element pivotally mounted upon the locking element for movement therewith and also with respect thereto, a stop 25 for limiting the movement of said second element for movement about its point of pivotal connection with said locking element, an actuating member pivotally mounted with respect to the said support, and an arm on said actuating 30 member, said arm in one position of the actuating member, serving as another stop for limiting movement of the said second element about its point of pivotal connection with said locking element, said arm in one direction of movement of 35 said actuating member, engaging an edge of said second element to bodily shift the latter to move the locking element about its pivot out of engagement with said shoulder, to release the said retainer.

40 14. In a vending machine an article support, a pivotally mounted retainer co-operating with the support to hold the article thereupon, a shoulder on the retainer, a pivotally mounted locking element, means tending normally to position said element to be engaged by said shoulder to lock said retainer, a second element pivotally mounted upon the locking element for movement therewith and also with respect thereto, a stop for limiting the movement of said second 45

element about its point of pivotal connection with said locking element, an actuating member pivotally mounted with respect to the said support, and an arm on said actuating member, said arm in one position of the actuating member, serving as another stop for limiting movement of the said second element about its point of pivotal connection with said locking element, said arm in one direction of movement of said actuating member, engaging an edge of said second element to bodily shift the latter to move the locking element about its pivot out of engagement with said shoulder, to release the said retainer, said actuating member constituting an additional article retainer co-operating with said support. 10 15. In a vending machine an article support, a pivotally mounted retainer co-operating with the support to hold the article thereupon, a shoulder on the retainer, a pivotally mounted 20 locking element, means tending normally to position said element to be engaged by said shoulder to lock said retainer, a second element pivotally mounted upon the locking element for movement therewith and also with respect thereto, a stop for limiting the movement of said second element about its point of pivotal connection with said locking element, an actuating member pivotally mounted with respect to the said support, an arm on said actuating member, 30 said arm in one position of the actuating member, serving as another stop for limiting movement of the said second element about its point of pivotal connection with said locking element, said arm in one direction of movement of said 35 actuating member, engaging an edge of said second element to bodily shift the latter to move the locking element about its pivot out of engagement with said shoulder, to release the said retainer, and means for positioning said retainer into an active position with respect to the support and for moving said shoulder to a position to engage said locking element, the said locking element yielding under the action of the last said means. 40 45
